UNITED STATES PATENT OFFICE.

MICHEL MARSON, OF CHICAGO, ILLINOIS.

HORSESHOE-PAD.

SPECIFICATION forming part of Letters Patent No. 760,796, dated May 24, 1904.

Application filed February 2, 1903. Serial No. 141,589. (No model.)

To all whom it may concern:

Be it known that I, MICHEL MARSON, a citizen of the United States, residing at Chicago, in the county of Cook and State of Illinois, have 5 invented certain new and useful Improvements in Horseshoe-Pads; and I do hereby declare the following to be a full, clear, and exact description of the invention, such as will enable others skilled in the art to which it app-10 pertains to make and use the same.

My invention relates to a novel construction in a rubber horseshoe-pad, the object being to provide a pad which will act in the manner of a bellows to throw out snow and mud 15 to prevent balling and simultaneously provide greater adhesion to prevent slipping, and which, further, is so constructed as to distribute pressure on the hoof in the most health-20 and advantageous manner; and it consists in the features of construction and combinations of parts hereinafter fully described and claimed.

In the accompanying drawings, illustrating my invention, Figure 1 is a bottom plan view 25 of a horseshoe provided with a pad constructed in accordance with my invention. Fig. 2 is a section of same on the line 2 2 of Fig. 1.

My said pad consists of a flat pad A, adapted along its edges to be interposed between 30 the horseshoe B and the hoof and which is provided at its middle portion with a downwardly-extending annular flange or rib C, forming an inverted cup D. The said flange or rib C is wider at the forward end than at 35 its sides, while at its rear end it is enlarged and extended upwardly above the plane of A to form a heavy pad E, which supports the frog of the hoof and which extends downwardly somewhat lower than the side and forward portions of said rib or flange C. The latter is beveled on its inner face, so as to 40 make said cup D flaring. The said rib or flange C, with its extended pad E, fills the entire recess of the horseshoe B and extends 45 below the lower face of the latter, its depth being determined by the character of the shoe, the depth being greater when the shoe is provided with calks than in the so-called "slipper" or light shoe free of calks.

It is a well-known fact that rubber shoes 50 will not act to prevent slipping in wet weather,

but serve as cushions to ease the hoofs and prevent undue hardening of the latter. In most cases I have found that all rubber horseshoes are very apt to take up and retain snow 55 and mud, which becomes rapidly compressed and hardened therein and greatly interferes with proper stepping of the horse, and also that such shoes do not adhere sufficiently to create the friction necessary to prevent un-60 due slipping.

The action of the cup D is as follows: When the hoof is placed on the ground, the pad E and the flange C are compressed, and the contained air is thus also compressed and 65 causes the top wall to bulge. The pad and flange also spread and act to cling to the ground to an extent to insure sufficient friction to prevent slipping. Upon raising the hoof the top wall of the cup again assumes 70 its normal position and by this action serves to throw out any mud or snow which might have found its way into the said cup. The lateral motion of the flange C also serves to dislodge mud or snow adhering to the horse-75 shoe B.

When the shoe is provided with sharp calks F and G, as illustrated, the latter preferably extend slightly lower than the flange C, as they generally sink into the ground sufficiently 80 to avoid interference with the action of the said pad while preventing undue compression, and thus increasing the life of the latter. In very slippery weather it is absolutely necessary to employ calks, as no rubber pad can absolutely prevent slipping, particularly when the load drawn is heavy and the motion slow. 85

I claim as my invention—

A horseshoe-pad consisting of a flat portion, an enlarged and upwardly-extending portion 90 at the rear of said flat portion to support the frog of the hoof, said portions adapted to contact directly with the hoof, and a central downwardly-extending annular flange on said flat portion forming an imperforate cup, all 95 of said parts being imperforate.

In testimony whereof I affix my signature in presence of two witnesses.

MICHEL MARSON.
